UNITED STATES PATENT OFFICE.

CHARLES B. JAHNKE, OF BELOIT, WISCONSIN, ASSIGNOR TO FAIRBANKS, MORSE & CO., OF CHICAGO, ILLINOIS, A CORPORATION OF ILLINOIS.

OIL-ENGINE CONTROL.

Application filed August 14, 1924. Serial No. 732,031.

My invention relates to deflecting plates for controlling the spray of fuel as injected into the pre-combustion chamber of an internal combustion engine, and more particularly relates to improvements in that type of apparatus disclosed in U. S. Patent 1,337,771, issued to Hobart & Jahnke.

The object of my invention is to provide means on such a deflecting plate for removing any carbon deposit which may have accumulated on the injector nozzle.

Another object of my invention is to provide a controllable method of operating an internal combustion engine at light loads through the use of such deflecting plates whereby a greater economy and efficiency may be secured at those loads.

Another object of my invention is to provide such deflecting plates which are detachable from the controlling means, thereby making it possible to use in the construction of these plates special types of heat-resisting material, such as nichrome and the like.

Although my invention consists largely in the construction and arrangement of parts hereinafter described and particularly pointed out in the claims, yet I do not limit my invention to the precise form, construction or arrangement of parts shown or the several parts thereof, inasmuch as various alterations may be made without changing the scope of my invention.

The further objects and advantages of my invention will appear from the following descriptions and drawings of my device. In the drawings Fig. 1 is a sectional view of the combustion end of an internal combustion engine employing an approved form of my device. Fig. 2 is an enlarged sectional view of the deflecting device as shown in Fig. 1. Fig. 3 is a sectional view of the deflecting device shown in Fig. 1, shown in its "out-of-action" position. Figs. 4 and 5 are of an approved form of deflection plate. Figs. 6, 7 and 8 are views partially in section of a modified form of my deflecting device, and Figs. 9, 10 and 11 are views of another modified form of my deflecting device.

Referring by numerals to the drawings, 10 designates a pre-combustion chamber which may be of any approved type and into which the fuel is injected by means of the injector 11, which may be of any suitable form, preferably of the single-

tube type having a fuel inlet such as 21. In conjunction with the chamber 10 may be employed a temporary hot mechanism as hot tube 12, set forth in Patent No. 1,159,341, issued November 2, 1915, and which is adapted to be heated from the outside by a torch or other suitable mechanism for the purpose of starting. 13 designates a deflecting plate of the type set forth in Patent No. 1,337,771, issued April 20, 1920, which is controlled by any suitable means such as the rod 14 and the handle 15 for the purpose of deflecting the flow of fuel from the nozzle of the injector 11 towards the hot tube 12 when the engine is being started. It is evident that by turning the handle 15, this deflecting plate 13 may be moved from the position shown in Fig. 2, which is the normal position for starting, toward that shown in Fig. 3, in which position the deflecting plate is entirely out of the line of flow of the fuel from the injector 11. This deflecting plate may be employed for purposes other than starting which will be hereinafter set forth.

It has been found that in employing low grade fuel oils that there is a tendency with many of them towards a formation of a considerable deposit of carbon on the end of the nozzle of the injector 11. It is evident that this carbon formation interferes with the successful operation of the engine, and I have provided a means for removing this formation whenever desired by the use of a projection 16 on the deflection plate 13, so constructed and so placed that when the handle 15 is turned from the position as shown in Fig. 3 to the position as shown in Fig. 2, the projection 16 will pass across the face of the nozzle of the injector 11 and in close proximity thereto, the result being that any carbon deposit on the end of the nozzle of the injector 11 will be scraped off by the projection 16. It is evident that this projection may be of any suitable form or shape.

When the engine is running at or near full load, the deflection plate is preferably removed from the path of the injected fuel by means of the handle 15 and rod 14. I have found, however, that when operating at light loads it is advantageous to introduce this deflection plate in the line of flow of the injected fuel, the result being that the fuel is deflected or spattered onto the walls 110

of the pre-combustion chamber, thereby giving a more complete combustion at these loads. Under such conditions and when employing the hot tube 12 for starting, it is preferable not to permit this deflected fuel to enter the hot tube, as is the case when starting the engine. In order to overcome this difficulty, I prefer to employ a deflecting plate with a deflecting surface which has a variable degree of angularity with respect to the axis of the plate. One form of such a plate is shown in Figs. 6, 7 and 8. 17 denotes the hub of the plate which may be attached to the rod 14 by means of set 18 screws or pins passing through the hole 18. At 16 is shown the projection or scraper for the purpose of removing carbon deposit, and at 19 is shown the surface upon which the fuel preferably impinges during starting. The angle of this surface 19 with respect to the axis of the plate 13 is such that the fuel will be deflected into the hot tube 12. The surface 20 into which the surface 19 merges, has, however, an angular disposition with respect to the axis of the plate 13 which varies from the angular disposition of the surface 19 sufficiently so that the fuel will not be deflected into the tube 12 but onto the inner surface of the pre-combustion chamber 10. It is evident, therefore, that by employing a deflecting surface on the plate 13 which has a varying angularity with respect to the axis of the plate, and by adjusting the position of this surface below the injector 11, I may deflect the flow of the fuel from the injector 11, either into the hot tube 12, such as would be done at starting, or onto the walls of the combustion chamber, such as would be done when running at light loads.

In Figs. 9, 10 and 11 I have shown a modified form of this deflecting plate in which a plurality of deflecting surfaces are employed on either side of projection 16, one surface being employed for starting, the other for running at light loads. It is evident that there are a number of forms which may be employed to accomplish the purposes as set forth.

50 I have found it desirable to make these plates of some heat-resisting material such as nichrome, for example, and, in order to save material in this construction, I prefer to make these plates detachable as shown. 55 It is evident, however, that they may be made integral with the controlling means and still be within the scope of my invention.

I claim:

60 1. An adjustable plate adapted to deflect at a plurality of selected angles, the flow of fuel emitted from the injector nozzle of an internal combustion engine, abrading means on said plate for removing carbon deposit on the fuel nozzle.

2. In combination with a fuel injector nozzle in an internal combustion engine, means for removing the carbon deposit from the nozzle, comprising a scraper member adapted to be moved across the end of the nozzle, 70 said member comprising a plurality of fuel deflecting surfaces, each disposed at a different angle to said nozzle.

3. A member adapted selectively to deflect in one of several predetermined directions, the flow of fuel emitted from the injector nozzle in an internal combustion engine, said member comprising a plurality of deflecting surfaces set at different angles to said nozzle, and a scraper adapted to be 80 moved across the end of the nozzle.

4. A detachable deflecting plate adapted to divert selectively at a plurality of different angles, the flow of fuel emitted from the injector nozzle in an internal combustion engine, said plate comprising fuel deflecting surfaces and a scraper adapted to be moved across the end of the nozzle.

5. A deflecting plate adapted to deflect the flow of fuel emitted from the injector 90 nozzle in an internal combustion engine, a deflecting surface on said plate having a plurality of different degrees of angularity with respect to the axis of said nozzle, said plate comprising a cleaning member for said 95 nozzle.

6. A movable plate adapted to divert at one of a plurality of angles, the flow of fuel emitted from the injector nozzle in an internal combustion engine, a scraping edge 100 on said plate, adapted for cleaning said nozzle, a deflecting surface on said plate having varying degrees of angularity with respect to the axis of said nozzle, means for controlling the position of said plate with respect to the injector nozzle.

7. A movable plate adapted to deflect the flow of fuel emitted from the injector nozzle in an internal combustion engine, a plurality of deflecting surfaces on said plate, said surfaces being of different degrees of angularity with respect to the axis of said nozzle and a scraper on said plate, apart from said deflecting surfaces, adapted to move in close proximity to the end of the injector nozzle 115 for cleaning the surface adjacent said nozzle.

8. In an internal combustion engine in combination with a pre-combustion chamber and an injector extending through the wall thereof, a deflecting plate adapted to deflect selectively the flow of fuel from the injector nozzle, at a plurality of different angles to the nozzle axis, a scraper on said plate adapted to be moved across the face of the 120 nozzle and in close proximity thereto, for the removal of solid deposit.

9. In an internal combustion engine in combination with a precombustion chamber, an injector extending through the wall 130

thereof, a deflecting plate having deflecting surfaces of several different degrees of angularity with respect to the axis of the injector and adapted to deflect the flow of fuel from the injector nozzle, according to the surface interposed in the fuel stream, a scraper integral with said plate adapted to be moved across the face of the nozzle for removing solid deposits therefrom, a manual positioning means and a resilient retention element for said plate, external to said engine.

10. In an internal combustion engine in combination with a precombustion chamber, an injector extending through the wall thereof, a deflecting plate having deflecting surfaces of several different degrees of angularity with respect to the axis of the injector and adapted to deflect the flow of fuel from the injector nozzle, according to the surface interposed in the fuel stream, a scraper integral with said plate adapted to be moved across the face of the nozzle and in close proximity thereto to clean said nozzle, and manually controlled means extending through the wall of said chamber for varying the relative position of said plate to said nozzle.

CHARLES B. JAHNKE.
